UNITED STATES PATENT OFFICE

CHARLES A. SPAUGH, OF DURHAM, OKLAHOMA

FENCE POST BRACE

Application filed January 27, 1930. Serial No. 423,837.

The present invention contemplates a novel construction of means for bracing a corner fence post, or any ordinary post used in conjunction with means for stretching the fence fabric, the invention residing in the construction, combination and arrangement of parts as claimed.

In the drawings forming part of this application like numerals of reference indicate 10 similar parts in the several views, and wherein:

Figure 1 is a view of a fence post braced in accordance with the present invention, and also showing how the fence post is used 15 in connection with means for stretching the fencing wire or fabric.

Figure 2 is a sectional view on line 2—2 of Figure 1.

Figure 3 is a view in elevation of one of 20 the anchors for the post.

Figure 4 is a view taken at a right angle to Figure 2.

Figure 5 is a sectional view on line 5—5 of Figure 1.

Figure 6 is a view showing how a corner post is braced in accordance with the present invention.

Figure 7 is a sectional view on line 7—7 of Figure 6.

Figure 8 is a sectional view on line 8—8 of Figure 6.

Figure 9 is a view of a slightly modified construction.

Figure 10 is a sectional view on line 10—10 of Figure 9.

Figure 11 is a perspective view of one of the brackets supported by the post.

Referring to the drawings in detail, and more particularly to Figures 1 to 5 inclusive, I have illustrated a fence post constructed of a single piece of metal, and preferably of U-shape formation in cross section as indicated at 10. This post is 20 preferably formed with a longitudinal groove 11 which receives a clamping bar 12, attached to the post in any suitable manner, the fence wires or the like being adapted to be clamped between the post 10 and the bar 12 as will be readily understood. The spaced 45 parallel side members 13 of the post are

connected together at suitably spaced points by bolts 14, while surrounding each bolt is a spacing sleeve 15 which construction materially strengthens the post structure in its 55 entirety. A portion of the groove 11 adjacent the lower end of the post is filled with a piece of metal 16 which may be attached to the post in any suitable manner, while carried by this filling element 16 is an 60 anchor plate 17.

For the purpose of bracing the post I employ a plurality of anchors, preferably of the construction illustrated in Figures 3 and 4, and adapted to be partly driven into the ground. Each anchor is preferably 65 tapered toward one end, and is indicated generally at 18, while each anchor is also formed with tapered ribs 19 arranged in right angular relation. It will be noted upon inspection of Figure 5 that the ribs 19 projecting from opposed sides of the anchor are slightly wider than the ribs projecting from the remaining sides thereof, although all of these ribs are formed with openings 20 adjacent the upper end of the anchor.

These openings may be used in conjunction with some suitable tool for lifting the anchors from the ground, but are primarily intended for use in connection with the brace rods which connect the anchors with the posts proper as clearly illustrated in Figure 1. It will be noted, however, that each anchor is provided with a reduced head portion 21 by means of which the 75 anchor is effectively driven into the ground.

As clearly illustrated in Figure 5, each brace rod 22 receives in its lower end, a threaded bolt 23, the latter terminating to provide a hook 24 adapted to pass through one of the openings 20 in the adjacent rib 19 of the anchor. Manifestly the bolt 23 is adjustable longitudinally of the brace rod 22, so that in reality the length of the latter can be varied as the occasion may require. The upper end of each brace rod 22 is connected with the post proper by means of a bracket 25, there being one of these brackets for each brace rod 22. The brackets are bolted or otherwise suitably secured 95 to the fence post, while each bracket is 100

formed with spaced apertured lugs 26 between which the upper end of the brace rod is secured.

For bracing an ordinary fence post, under ordinary conditions, or when the particular fence post is used in conjunction with means for stretching the fence fabric, two of the brace rods 22 are preferably employed and arranged at opposite sides of the post as clearly illustrated in Figure 1. In this figure it will be noted that a block and tackle indicated generally at 28 is supported upon the post by a suitable band or ring 28', and also connected with a clamp 29 adapted to be attached to the adjacent end of the fence fabric in any suitable manner. This construction, however, does not form any part of the present invention, which of course resides in the novel construction of means utilized to properly and effectively brace the fence post when used in the manner illustrated in Figure 1.

In Figures 6 to 8 inclusive I have illustrated how the invention is used in conjunction with a corner post for the purpose of bracing two adjacent sides of the post. In these figures the post indicated at 30 is preferably of U-shape formation in cross section. Arranged on one side of the fence post is a bracket 33 which is secured thereto by spaced upper and lower bolts 34 which pass through the parallel side members of the fence post, while this bracket 33 is formed with spaced apertured lugs 35 between which the adjacent end of the brace rod 36 is connected. This brace rod is of the same construction as hereinabove described, including a longitudinally adjustable bolt 37 which is adapted to be connected with the adjacent anchor 38 all of which parts are identical in construction with that described in connection with Figures 1 to 5 inclusive.

Mounted on the same side of the fence post but adjacent the lower end thereof is a similar bracket 39, secured to the post by upper and lower bolts 40, the bracket 39 being formed with apertured lugs 41 which are arranged in contacting engagement with each other as clearly illustrated in Figure 8. These lugs receive the hook like extremity 42 of an adjustable bolt 43 threadedly received by the adjacent end of an auxiliary brace rod 44 which is clamped to the brace rod 36 at an appropriate point in its length as indicated at 45.

For the purpose of bracing the adjacent side of the same post, I employ a pair of brackets of the construction illustrated in Figure 11, and these brackets are arranged between the spaced parallel flanges or side members of the post as illustrated. These opposed ends are bent upon themselves to form loops 47. The loops 47 of the uppermost bracket 46 receive the bolts 34 of the bracket 33, so that the same bolts are em-

ployed to secure both of these brackets to the post; while the loops 47 of the lowermost bracket 46 accommodate the bolts 40 of the bracket 39, so that both of these latter mentioned brackets are secured to the post by the same bolts. Each of the brackets 46 is also formed with apertured lugs 48, the lugs of the uppermost bracket being spaced apart to receive the adjacent end of the brace rod 49 therebetween, the lower end of this rod being connected with the anchor 38 in the same manner as hereinabove described in connection with the anchor 36. However, the apertured lugs 48 of the lowermost bracket 46 are arranged in contacting engagement as illustrated in Figure 8, and receive the hook like extremity 49 of the auxiliary brace rod 50, which is clamped to the brace rod 49 at an appropriate point in its length as at 51. It is obvious from the construction illustrated and described in Figures 6 to 8 inclusive, that the fence post is not only braced at spaced upper and lower points, but that two adjacent sides of the post are braced, which is very desirable with corner posts of a fence or the like.

In Figures 9 and 10 I have illustrated a slightly modified form of the invention, which is the same as the structure illustrated in Figure 1, except that the brace rods 52 which have their corresponding upper extremities secured to brackets 53 attached to opposed sides of the fence post, and their lower extremities secured to the anchors 54, all of which parts are of the same construction as hereinabove described, but are further braced by auxiliary brace rods 55. The outer end of each auxiliary brace rod 55 is attached to a clamp 56 which embraces the brace rod 52, while the adjustable bolt 57 of the auxiliary brace rod has its extremity connected with a bracket 58 secured to the adjacent side of the fence post and of the same construction as the bracket 53. Otherwise the construction is the same as that illustrated and described in Figure 1.

While it is believed that from the foregoing description the nature and advantages of the invention will be readily understood, I desire to have it known that I do not limit myself to what is herein illustrated and described, and that such changes may be resorted to when desired as fall within the scope of what is claimed.

What I claim is:

1. The combination with a fence post of U-shape formation in cross section, of a bracket arranged on one side of the post, an additional bracket arranged between the spaced parallel side members of the post, bolts common to both of said brackets for attaching the latter to the post, spaced apertured lugs projecting from each bracket, brace rods having their corresponding upper extremities connected with said lugs, an-

chors adapted to be driven into the ground, and a longitudinally adjustable element forming part of each brace rod and terminally connected with the adjacent anchor.

2. The combination with a fence post of
- 3 U-shape formation in cross section, of a pair of brackets mounted upon two adjacent sides of the post, bolts common to both of said brackets for attaching the latter to the post, brace rods having their corresponding upper extremities connected with said brackets, anchors adapted to be driven into the ground, and connected with the adjacent lower ends of said brace rods, additional brackets secured to the same two adjacent sides of the post adjacent the lower end thereof, and auxiliary brace rods connecting the last mentioned brackets with the first mentioned brace rods at appropriate points in their length.
- 20 In testimony whereof I affix my signature.
CHARLES A. SPAUGH.
